UNITED STATES PATENT OFFICE.

SIDNEY E. MEYERS, OF BUFFALO, NEW YORK, ASSIGNOR, BY DIRECT AND MESNE ASSIGNMENTS, TO MELCO ENGINEERING CORPORATION, A CORPORATION OF NEW YORK.

OIL BURNER.

Application filed May 29, 1924. Serial No. 716,659.

This invention relates to improvements in oil burners.

The principal objects are to effect an intimate combustible mixture of air and thoroughly and substantially completely vaporized oil while avoiding any carbon deposits within the burner structure, to deliver the fuel mixture uniformly throughout the area of its discharge opening and in such manner that the resultant flame is highly efficient and free from any blow torch effect or objectionable degree of noise, to avoid destructive heating of the burner casing or pot, and to provide for low pressure operating conditions.

The invention consists generally in novel features of structure and combination which will be set forth in detail as the description proceeds.

In the accompanying drawings:

Figure 1 is a plan view showing a burner in accordance with the invention as installed in a heating furnace.

Figure 2 is a view drawn to larger scale showing the burner partly in section and partly in plan, the section being taken on line 2—2 of Figure 3.

Figure 3 is a vertical section on the line 3—3 of Figure 2.

Figure 4 is a cross section on the line 4—4 of Figure 3.

Figure 5 is a plan view of the vaporizing element.

Figure 6 is a side elevation of the same.

The burner B is provided at the end of an air trunk T and is supplied with oil by a pipe O. The burner includes a casing which, according to the invention, has a bottom 1, a helical vertical wall 2 and a top plate 3. The walls 1, 2 and 3 provide a chamber 4 which, owing to the spiral form of its vertical perimeter wall, causes the gasified fuel to have a whirling motion which prolongs its contact with the adjacent heated surfaces and effects its intimate admixture with the air supplied by the trunk T and by which the combustible mixture is completed. The gaseous fuel in the chamber 4 issues in a state of combustion from the burner through an opening in the top plate 3, combustion being completed outside the burner. The fuel discharge opening, as 5, is co-axial with the axial point of origin of the helical wall 2 and is preferably formed

in an annular section 3^a which is functionally a part of the top plate and is removably supported on a ledge 6 delimiting an opening 7 in the top plate. By thus providing the opening 5 in a separable top plate section 3^a the size of the fuel discharge opening may be readily selected as conditions may require, it being understood that different sections 3^a will have openings of different diameters and that all that is necessary in any case is to employ a section having an opening of a size best adapted for the requirements of the particular installation.

The air trunk T is connected tangentially to the burner casing and is in open communication with the chamber 4, the vertical walls of said trunk being connected at their ends to the ends of the helical wall 2 of said chamber 70 whereby the latter forms in effect a laterally disposed helical continuation of the air trunk.

The burner also includes a vaporizing element upon which the oil discharged by the pipe O is deposited and which is so arranged that its temperature is raised suitably above the vaporizing point of the oil by heat radiated from within the chamber 3. As shown and preferred the vaporizing element consists of a plate 8 which is arranged partly within the discharge end of the trunk T and partly within the portion of the chamber 3 adjoining such discharge end, the sides of said plate conforming to the helical curvature of the wall 2. The plate 8 extends within the chamber 3 for a fraction of a circle, preferably approximately ninety degrees, and is inclined downward in the direction in which it extends into said chamber, being provided at its end located within the trunk T with a depending transverse supporting flange 9 by which such end of the plate is supported at the elevation desired. The oil pipe O adjacent the burner has a lateral extension 10 arranged to overlie the plate 8 whereby the oil delivered by the pipe O will be deposited on said plate. The oil supplied to the chamber 3 is initially ignited by a gas burner 11 which is connected to a gas pipe 12 and is arranged under the raised end of the plate 8. At a point in advance of the gas burner 11 the plate 8 is

formed with slots 13 or other suitable openings through which the flames from the burner 11 may pass. The oil is prevented from flowing prematurely from the plate 8 by ridges 14 and 15 arranged on the upper face of the plate, the ridges 14 circumscribing the slots 13 and the ridges 15 extending along the sides of the plate.

In case any excess oil should be deposited in the chamber 4, due to overfeeding or to a failure of vaporization or ignition from any cause whatever, such excess will flow away through a pipe 16 which may be connected to the vertical wall of said chamber at any point except under the plate 8, the pipe 16 leading to an oil recovery tank (not shown).

It will be noted that the plate 8 with its flange 9 provides a complete barrier to protect the flames of the gas burner 11 from the air blast discharged by the trunk T and that all of the air is caused by the flange 9 to pass above the plate 8.

In operation the gas is lighted at the burner 11 and burns under the plate 8 which becomes moderately heated. Oil and air are admitted simultaneously through the pipe O and trunk T respectively. The oil being deposited upon the sloping plate 8 flows toward its lower end and is vaporized on the way by the heat of said plate. The gas flames issuing through the openings 13 ignite the oil vapor and combustion commences. The helical shape of the chamber 4 causes the vapor and air to revolve at high speed which promotes the intimacy of the mixture and shortens the time required for its production. A centrifugally formed rapidly whirling stratum of air surrounds the burning mixture in the chamber 4 and has a cooling effect on the walls of said chamber whereby destructive heating of the burner casing is avoided. The combustion which occurs within the chamber 4 supplies the radiant heat necessary for maintaining a vaporizing temperature in the plate 8. The burning rapidly whirling mixture issues uniformly throughout the area of the opening 5 and has a natural centrifugal spread which, combustion being completed outside the burner, results in a flame of the most efficient character for heating purposes, that is to say a relatively low and wide fluffy or bush-like flame. Once having established combustion the process is automatic and the operation of the gas burner 11 may be discontinued.

The oil may be supplied to the furnace by gravity feed or under just sufficient pressure to insure its deposit at the required rate and the air, which is not intended to have any atomizing action, is forced through the trunk T under low pressure, e. g. approximately four or five pounds, which is sufficient for its delivery in the amount required to insure complete combustion and to develop the requisite whirling movement of the mixture.

It is particularly to be noted that the vaporizing element, in this instance the plate 8, is so arranged that it is heated by radiation from the flame of the mixture burning in the chamber 4 to a degree which prevents it from being cooled below the vaporizing point of the oil by the current of air issuing from the trunk T. It follows that the plate 8 is always maintained at a temperature which will effect vaporization of the oil and that the deposit of carbon anywhere within the chamber 4 is prevented. I have found that any "free" carbon which may lodge on the plate 8 is swept away as soon as deposited by the mechanical action of the current of air passing over said plate. In other words non-volatile carbon will not deposit on a vaporizing surface which is being swept by a copious supply of air.

Having fully described my invention, I claim:

1. An oil burner comprising a chamber having a helically curved vertical wall adapted to cause the flame to whirl and after leaving the burner to spread, a top wall provided with a circular fuel discharge opening arranged co-axially with the axial point of origin of said vertical wall, an oil vaporizing element so arranged in said chamber that it is raised by the radiated heat of the mixture burning in said chamber to oil vaporizing temperature, said vaporizing element being located at one end of the helically curved wall, means for depositing oil on said vaporizing element and an air trunk communicating with said chamber and extending tangentially thereto and arranged to direct the current of air over the vaporizing element to produce a scrubbing action on the same.

2. An oil burner comprising a chamber having a helically curved vertical wall to cause the flame to whirl, a top wall provided with a circular fuel discharge opening arranged co-axially with the axial point of origin of said vertical wall, an air trunk communicating with said chamber and extending tangentially thereto, an arcuate oil vaporizing plate extending downward into said chamber from the discharge end of said trunk, said plate having a transverse depending supporting flange at its higher end, means for depositing oil on said plate located in the path of the current of air entering the chamber to maintain the oil depositing means cool and prevent the same from clogging, and a pilot burner arranged under said plate, the latter having openings through which the flames from said pilot burner may pass.

3. An oil burner comprising an air trunk and a chamber laterally offset from and communicating with the discharge end of said air trunk which adjoins said chamber tangentially, said chamber having a helical vertical wall and a top provided with a circular

fuel discharge opening arranged co-axially with the axial point of origin of said wall, an oil vaporizing plate positioned in the discharge end of said air trunk and extending into said chamber, said plate being swept by the cool air from said trunk and heated to vaporizing heat by the radiation within

10

said chamber, and an oil supply pipe having its discharge end arranged to deposit oil on said plate.

In testimony whereof I affix my signature.

SIDNEY E. MEYERS.
